A. F. RUGGIERO

ANTICREEPING DEVICE.

Filed Feb. 14, 1925

Patented June 9, 1925.

1,540,957

UNITED STATES PATENT OFFICE.

ANGELO F. RUGGIERO, OF GOLD CREEK, MONTANA.

ANTICREEPING DEVICE.

Application filed February 14, 1925. Serial No. 9,154.

To all whom it may concern:

Be it known that I, ANGELO F. RUGGIERO (commonly known as ANGELO F. ROGERS), a citizen of the United States, residing at 5 Gold Creek, in the county of Powell and State of Montana, have invented certain new and useful Improvements in Anti-creeping Devices, of which the following is a specification, reference being had to the 10 accompanying drawings.

This invention relates to certain improvements in anti-creeping devices for railroad rails and it is an object of the invention to provide a device of this general character 15 which can be readily and effectively applied to the base flanges of a rail and engage a cross tie in a manner to effectively hold the rail against creeping.

The invention consists in the details of 20 construction and in the combination and arrangement of the several parts of my improved anti-creeping device for railroad rails whereby certain important advantages are attained and the device rendered simpler, less expensive and otherwise more convenient and advantageous for use, as will be hereinafter more fully set forth.

The novel features of my invention will hereinafter be definitely claimed.

30 In order that my invention may be the better understood, I will now proceed to describe the same with reference to the accompanying drawings, wherein:—

Figure 1 is a view in top plan illustrating 35 an anti-creeping device constructed in accordance with an embodiment of my invention and in applied position;

Figure 2 is a view in side elevation of the structure as illustrated in Figure 1;

40 Figure 3 is a view in bottom plan of the structure as illustrated in the foregoing figures;

Figure 4 is a sectional view taken substantially on the line 4—4 of Figure 2;

45 Figure 5 is a fragmentary view in perspective of the rail and tie engaging member as herein disclosed.

As disclosed in the accompanying drawings, my improved anti-creeping device 50 comprises an elongated shank 1 having one end portion turned, as at 2, to provide a hook to engage over a base flange of a rail. The major portion of the hook 1, as herein disclosed, is angular in cross section but 55 its opposite end portion is rounded, as at 3, to permit a nut 4 to be threaded thereon.

The rail and tie engaging member M, as herein disclosed, is formed of a single piece of material and comprises a pair of spaced plates 5 and 6 having their outer vertical margins connected by an intermediate plate or web 7 preferably integrally formed therewith. The inner marginal portions of the plates 5 and 6 are provided with the notches 8 which snugly receive a flange of 65 a rail and the member M is maintained in desired firm or tight engagement with the flange by the shank 1 hereinbefore referred to.

The intermediate web or plate 7 at a 70 point below the notches 8 is provided with an opening 9 through which the portion 3 of the shank 1 is disposed and the applied nut 4 contacts with said plate or web 7 from without. By proper turning of the 75 nut 4 the member M is firmly forced upon one flange of the rail while the hook 1 is drawn into firm and close contact with the opposite flange. The lower margin of the plate 6 is provided with an outstanding arm 80 10 of desired length and which terminates in a depending flange 11 adapted to have direct contact with a tie T whereby creeping of a rail in one direction is effectively prevented. If it is desired to prevent creeping of the rail in the opposite direction, my 85 improved device can be readily and conveniently reversed.

It is also to be noted (Figure 3) that the arm 10, when the member M is in applied 90 or working position, is located entirely beneath the rail.

It is also to be understood that my improved device may be made in such sizes or dimensions as the necessities of practice 95 may require and particularly as determined by the size of the rail to which it is applied.

After the nut 4 has been applied, the same is preferably held against displacement by inserting a cotter pin 12 or the like through 100 the rounded portion 3 of the shank 1 outwardly of the nut 4 in close contact therewith.

From the foregoing description it is thought to be obvious that an anti-creeping 105 device for railroad rails constructed in accordance with my invention is particularly well adapted for use by reason of the convenience and facility with which it may be assembled and operated, and it will also be 110 obvious that my invention is susceptible of some change and modification without de-

parting from the principles and spirit there-
of and for this reason I do not wish to be
understood as limiting myself to the pre-
cise arrangement and formation of the sev-
eral parts herein shown in carrying out my
invention in practice except as hereinafter
claimed.

I claim:—

1. An anti-creeping device for a rail comprising a pair of plates connected by an intermediate plate, said first named plates being provided with notches to receive a flange of a rail, the intermediate plate having an opening positioned below the notches, a shank adapted to underlie the rail and having means to engage the second flange of the rail, said shank extending through the opening in the intermediate plate and a nut engageable with the shank outwardly of the intermediate plate but contacting therewith to hold the first named plates and the shank in proper engagement with the flanges of the rail, and a laterally disposed arm carried by one of the plates for contact with a tie.
2. An anti-creeping device for a rail comprising a pair of plates connected by an intermediate plate, said first named plates being provided with notches to receive a flange of a rail, the intermediate plate having an opening positioned below the notches, a shank adapted to underlie the rail and having means to engage the second

flange of the rail, said shank extending through the opening in the intermediate plate and a nut engageable with the shank outwardly of the intermediate plate but contacting therewith to hold the first named plates and the shank in proper engagement with the flanges of the rail, and a laterally disposed arm carried by the lower portion of one of the first named plates for contact with a tie.

3. An anti-creeping device for a rail comprising a pair of plates connected by an intermediate plate, said first named plates being provided with notches to receive a flange of a rail, the intermediate plate having an opening positioned below the notches, a shank adapted to underlie the rail and having means to engage the second flange of the rail, said shank extending through the opening in the intermediate plate and a nut engageable with the shank outwardly of the intermediate plate but contacting therewith to hold the first named plate and the shank in proper engagement with the flanges of the rail, and a laterally disposed arm carried by the lower portion of one of the first named plates for contact with a tie, the contacting end of the arm being provided with a depending flange.

In testimony whereof I hereunto affix my signature.

ANGELO F. RUGGIERO.
